United States Patent Office

Des. 211,080
Patented May 21, 1968

211,080

CAR WASH BUILDING

Richard J. Shelstad, Brookfield, Wis., assignor to Edick
Laboratories, Inc., Milwaukee, Wis., a corporation of
Wisconsin

Filed Jan. 5, 1967, Ser. No. 5,315

Term of patent 7 years

(Cl. D13—1)

Fig. 3

Fig. 4

FIG. 1 is a perspective view of a car wash building showing my new design;

FIG. 2 is a side elevation view;

FIG. 3 is an end elevation view; and

FIG. 4 is a top plan view.

The rear and right end of the building are unornamented.

I claim:

The ornamental design for a car wash building, substantially as shown and described.
